UNITED STATES PATENT OFFICE.

PHINEAS F. KING, OF CINCINNATI, OHIO, ASSIGNOR TO THE MOSLER BANK
SAFE COMPANY, OF SAME PLACE.

TIME-LOCK.

SPECIFICATION forming part of Letters Patent No. 450,293, dated April 14, 1891.

Application filed October 29, 1890. Serial No. 369,725. (No model.)

To all whom it may concern:

Be it known that I, PHINEAS F. KING, of Cincinnati, Hamilton county, Ohio, have invented certain new and useful Improvements 5 in Time-Locks, of which the following is a specification.

This invention relates to improvements in time-locks for use on safes, vaults, treasure-chests, &c., and the improvements will be 10 readily understood from the following description, taken in connection with the accompanying drawings, in which—

Figure 1 is a front elevation of a time-lock exemplifying my invention in its simpler form, 15 the usual front cover of the lock-case being removed to expose the interior, and a portion of the day-wheel being broken away to expose the mechanism in its rear; Fig. 2, a front elevation of the lock in its more refined form, 20 the simpler form being illustrated in Fig. 1 for the purpose of more ready explanation and understanding of the principle of the lock; Fig. 3, an elevation of a portion of the day-wheel, showing two exemplifying plans 25 for throwing the unlocking-pins out of action on any desired day; Fig. 4, a perspective view of a portion of the bolt; Fig. 5, an edge view of the day-wheel; Fig. 6, a plan and horizontal section of the refined lock of Fig. 2, the 30 case and bolt appearing in section in the plane of line *b*, while the time-dial and the closing-dial appear in section in the plane of line *a*; Fig. 7, a horizontal section of the simple lock of Fig. 1 in the plane of line *d*, and 35 Fig. 8 a central vertical section of the simple lock of Fig. 1.

Attention is directed to my patent, No. 211,409, of January 14, 1879, in which is set forth a time-lock whose time-disk receives 40 motion from two clock-movements through gearing and pawls and ratchets in such manner that both clock-movements running independently will drive the time-disk, the time-disk responding to the faster clock-movement 45 if the two clock-movements should not have the same rate of running.

In the accompanying drawings and giving consideration for the present only to Figs. 1, 50 7, and 8, which show the lock in its simpler form, A indicates the usual inclosing case of a time-lock; E, the usual movement-case dis-

posed therein and containing two clock-movements of usual construction and arrangement, (not shown;) C, the pinions driven by these respective clock-movements; D, two gears 55 on a common axis, driven by these pinions, respectively; E, the time-arbor revolved by the gears D; F, the time-disk, fast on the arbor E. Said arbor is shown as tubular and running on a post. G is a knurl exemplifying 60 a handle on the time-arbor E, by means of which the time-disk may be turned ahead by hand.

The parts thus far described involve nothing new in view of the earlier King patent. 65 The clock-movements run and give continuous rotary motion to the time-disk, the time-disk yielding to the influence of the faster movement if there should be lack of unison. This is done by ratchets *n* and pawls *o*, as in 70 the earlier King patent. Therefore the time-disk F may be assumed as in continual rotation in the direction of arrow C and moving at a regular rate of speed.

My time-disk F in the exemplification is to 75 rotate once in forty-eight hours. The hours may be indicated by graduations on the time-disk, and the time may then be read off by means of the pointer M. The time-disk, being a forty-eight-hour dial, might have the 80 forty-eight hours indicated on it; but it is just as well to limit the readings to those hours of special pertinence in time-locks for banking business. The pointer M in Fig. 1 shows it to be six o'clock in the evening. In twenty- 85 four hours the reading will be exactly the same; but the graduations on the opposite edge of the dial will then come into play, it being understood that the two sets of graduations are due simply to the fact that the dial 90 is a forty-eight-hour or two-day dial. The clock-movements being wound up, the dial is to be set by turning knurl G ahead until pointer M indicates correct local time, and it is quite immaterial which of the two sets of 95 graduations is employed. We will thus assume that we have the time-dial F running continuously at proper rate and indicating always the correct local time. This is merely a matter of setting and regulation, and is to 100 receive attention often or never, according to circumstances. This revolving time-disk is

to produce locking and unlocking movements of the lock-bolt at certain predetermined times.

Referring to Figs. 1, 7, and 8 of the drawings, H indicates the bolt, exemplified as a mere rod reciprocating vertically in the case, its upper position being its closed or locked position and its downward position that corresponding to the unlocked or open one; J, a spring exemplifying means for pressing and holding the bolt H into upward or locked position; K, a latch-lug upon the bolt, (see Fig. 4;) L, a spring-latch, hooking over the latch-lug when the bolt is down or in unlocked position; M, the stationary time-pointer before referred to. Bolt H is to be attached in any suitable manner to whatever bolt mechanism the time-lock is to control, so that when bolt H is up such bolt mechanism will be locked and when bolt H is down such bolt mechanism will be unlocked. In Fig. 1 the bolt is down in unlocked position, and it is so held by the latch L. If we should press latch L to the left, it will disengage from the latch-lug K, and spring J will then lift the bolt into locking position. It is the duty of connecting mechanism between the time-dial F and the bolt H to trip the latch at the predetermined locking hour and to depress the bolt and permit it to latch in unlocked position at the predetermined unlocking hour.

Proceeding with the drawings Figs. 1, 7, and 8, N indicates a star-wheel, hereinafter denominated the "day-wheel," consisting of a disk with eight teeth or points mounted for free revolution near the time-disk and bolt; O, an annular series of eight pins projecting from the rear face of the day-wheel, there being one pin for each of the points of the day-wheel, these pins being exemplified as screws whose points project through the day-wheel, (see Fig. 5;) P, a stop-ratchet on the arbor of the day-wheel to prevent the day-wheel being turned backward or to hold it in position where put; Q, a ledge projecting from the bolt H, (see Fig. 4,) in position to be engaged by the pins O in such manner that if the bolt be up in locked position the day-wheel pin will engage the ledge as the day-wheel revolves and pull the bolt down and allow the latch L to engage, such unlocking of the bolt taking place whenever the bolt is up and a pin O comes to the bolt-ledge, the pins clearing the bolt-ledge when the bolt is down. It should now be obvious that the bolt being down and latched, as in Fig. 1, we might turn the day-wheel in the direction of its arrow without having any effect upon the bolt, but that if the bolt be up and we turn the day-wheel a pin will engage and push the bolt down and allow it to be latched down. It is the duty of mechanism connected with the time-dial F to rotate the day-wheel one tooth each day, so that each day the bolt will be pushed down into unlocked position and allowed to latch in that position.

R indicates a disk, hereinafter termed the

"unlocking-disk," mounted on the time-arbor E and turning with the time-disk, but driven by pawl and ratchet m l, so that the unlocking-disk can be "set" by turning it ahead; S, two prongs projecting from the locking-disk in position to strike and release the latch L as these prongs pass the latch, there being two prongs on the disk simply because the time-dial is a two-day dial and the locking must be provided for each day; T, a disk, hereinafter termed the "unlocking-disk," similarly mounted on the time-arbor and revolving with the time-disk; U, two pins projecting from the face of the unlocking-disk, in position to engage the teeth of the day-wheel N as the three disks revolve, the effect being that the day-wheel is rotated one tooth at each passage of a pin U, or once each twenty-four hours, there being two of the pins U simply because the time-dial is a two-day dial.

In Fig. 1 the bolt is down and latched and one of the prongs S of the locking-disk, appearing in dotted line behind the day-wheel, is near the latch. The time-disk F and its disks revolve in the direction of the arrow c, and soon the prong referred to will strike the latch and unlatch the bolt and spring J will throw the bolt to locked position. When this prong has done this unlatching, the time-disk will have rotated till the opposite one of the prongs S is directly upward. Pointer M will then indicate on the time-disk that it is eight o'clock by local time and the upper one of the prongs S points to the figure "8." The locking will therefore occur at the time indicated by the pointing of prong S on the time-dial. It is immaterial which of the prongs S be looked at, for they both point to identical time-scales. If we desire the locking to take place at six o'clock instead of eight, we have only to turn the locking-disk R to the right, so that prongs S will point to six o'clock on the time-disk. The locking-disk can be turned and brought to any desired position on the time-dial. It will also be obvious that as the time-disk rotates it will in course of time bring the right-hand pin U into engagement with the upper tooth of the day-wheel N, and as it proceeds rotate the day-wheel one tooth. With the bolt in the unlocked position shown, the rotation of the day-wheel would have no effect on the bolt; but if the bolt is up in locked position then the advance of the day-wheel would have caused a pin O to press the bolt down into unlocked position. It should therefore be understood that each day a pin U will advance the day-wheel and cause the unlocking of the bolt. When the right-hand pin U finishes its performance of the unlocking office, the other pin U will be up under the pointer M, and pointer M will indicate six o'clock local time, and the pins U are seen to be adjusted at six o'clock local time. The hour of unlocking may be changed by adjusting the unlocking-disk T upon the time-disk, so that the pins U are opposite the desired unlocking

hour. It should now be understood that time-disk F is never adjusted except to maintain correspondence with local time, and that the locking hour is determined by setting prongs 5 S to the desired hour on the time-disk, and that the unlocking hour is determined by setting the pins U to the desired hour on the time-dial. It will be observed that there is no computation involved, no calculation of 10 length of interval between locking and unlocking, and no disturbance of local time reading to adjust the locking and unlocking time. Locking and unlocking times are adjusted by 15 separate pointers, each brought to point to the desired respective hour of action.

The lock thus far described is in its simpler form, the graduations on the time-disk being utilized for all the settings. To correct the time-disk to local time, we turn it by 20 means of knurl G. To set the unlocking-disk, we turn that disk on the time-dial by using our fingers on the prongs S. To set the locking-disk, we employ the fingers on the pins U; but it is highly desirable to avoid this fin- 25 gering, as one adjusting act may possibly disturb one previously made. I therefore prefer to provide separate side spindles geared to the locking and unlocking disks, so that those disks may be more conveniently ad- 30 justed, and I go farther and provide these side spindles with graduated dials, so that the setting of the disks may be effected without reference to the time-disk. Figs. 2 and 35 6 show the lock so arranged. I cover up all the mechanism seen in Fig. 1 with a front plate d, and I expose in front of this plate three dials—namely, the time-dial V, the locking-dial W, and an unlocking-dial X. Dial V moves directly with time-disk F and indi- 40 cates local time by stationary pointer M. This dial V may be graduated for the entire forty-eight hours, or such duplicate portions of the forty-eight hours as may be deemed useful. This dial V will never need setting 45 except to secure correspondence with local time. Pointers Y and Z are geared to the time-dial F and move continuously with it. Dial W is geared to the locking-disk R, and dial X is geared to the unlocking-disk T. 50 The three dials and the two pointers rotate continuously and in unison precisely as the two disks and time-disk go together in Fig. 1. The dials in Fig. 2 may be rotated by the handles e or any other suitable finger-piece 55 or key-piece. The hour-settings of the dials in Fig. 2 are precisely the same as in Fig. 1. The lock will close at eight o'clock. If we wish locking to occur at six o'clock, we turn dial W till the pointer stands at the figure "6," 60 the advancing of the dial causing an advance of disk R accordingly.

Fig. 6 shows the arrangement of gearing which will be self-explaining, it being proper, however, to explain that in the exemplification l is a ratchet-wheel fast on the time-arbor E, and m are pawls on the disks R and T, engaging this ratchet-wheel, so that the

time-arbor carries the two disks around and at the same time permits of the disks being moved ahead for purposes of adjustment, the 70 mechanism being the same as that employed to permit one of the clock-driven gears D to move in advance of the other, precisely as explained in the earlier King patent.

It will be readily understood that, if de- 75 sired, the geared side spindles may be retained as a mere means for adjusting the locking and unlocking disks, the dials W, V, and X and the pointers Y and Z and their gears being omitted, the readings being taken 80 directly from the time-dial, Fig. 1, and in such case it is quite immaterial what the proportion of the gearing is between the side spindles and the disks which they are em- 85 ployed to adjust; but it is preferred that sepa- 90 rate dials be employed, as in Fig. 2, and the graduations on these dials may be limited to such hours as are involved in the separate functions of the dials. This simplifies the settings and permits of the brief instructions "set to the three dials," which covers all that is needed by the user of the time-lock.

Returning again to Fig. 1, it is remembered that a pin O of the day-wheel N comes into action and unlocks the bolt each day. If we 95 wish the lock to remain on guard for any future day within the range of the day-wheel, we have only to suppress the pin O, which would come into action on that day. We may do this by taking the pin out or by means 100 of any other construction which will permit the shifting of the pin to inoperative position.

In Fig. 3 two teeth of the day-wheel are shown, illustrating two plans for shifting a pin into an inactive position. In one plan 105 the pin is to be removed, and it may be stored in the idle-hole f. In the other plan the pin is to be slid in the slot G inwardly far enough to escape the bolt-ledge.

There might be cases in which it was de- 110 sired that the lock remain on guard for several days consecutively, in which case several of the pins O would be thrown out of action. If all the pins should be removed, there would be a lock-out, for the day-wheel would never 115 open the bolt. I therefore prefer to provide the day-wheel with one immovable unlocking-pin, as at p. The day-wheel shown makes one revolution in eight days, covering a full 120 week, and an extra pin to insure unlocking. There is, however, no limit to the number of teeth and pins that the day-wheel may have. It might, if desired, have thirty-one, even, and the corresponding days of the week or month might be indicated on the day-wheel, 125 so that the proper pin or pins could be withdrawn without computation. It is my preference that whatever the number of days provided for in the day-wheel the clock-move- 130 ments should be arranged to furnish power for that number of days. Pin p would then furnish the safeguard against any lock-out due to the running down of the movement.

I claim as my invention—

1. In a time-lock, the combination, substantially as set forth, with clock-driven mechanism and a bolt, of a day-wheel engaging and unlocking the bolt several times each rotation, a time-arbor rotated continuously by said clock-driven mechanism, a projection carried by said time-arbor and arranged to give an unlocking impulse to the day-wheel once every twenty-four hours, and a projection carried by said time-arbor and arranged to lock the bolt once every twenty-four hours.
2. In a time-lock, the combination, substantially as set forth, with clock-driven mechanism, a bolt, a time-arbor driven continuously by the clock-driven mechanism, a projection carried by the time-arbor to lock the bolt each day, and a projection carried by the time-arbor to cause the unlocking of the bolt, of a day-wheel engaged and partially rotated each day by said last-mentioned projection, and a series of projections in said day-wheel, each arranged to engage and unlock the bolt, one or more of said day-wheel projections being removable out of the plane of engagement with the bolt.
3. In a time-lock, the combination, substantially as set forth, with clock-driven mechanism, a bolt, a time-arbor driven continuously by the clock-driven mechanism, a projection carried by the time-arbor to lock the bolt each day, and a projection carried by the time-arbor to cause the unlocking of the bolt, of a day-wheel engaged and partially rotated each day by said last-mentioned projection, and a series of projections in said day-wheel, each arranged to engage and unlock the bolt, one or more of said day-wheel projections being removable out of the plane of engagement with the bolt and one of said day-wheel projections being immovable out of said plane.
4. In a time-lock, the combination, substantially as set forth, with clock-driven mechanism, a bolt, a time-arbor driven continuously by the clock-driven mechanism, a projection carried by the time-arbor to lock the bolt each day, and a projection carried by the time-arbor to cause the unlocking of the bolt, of a day-wheel engaged and partially rotated each day and completely rotated every eight days by said last-mentioned projections in said day-wheel, each arranged to engage and unlock the bolt, one or more of said day-wheel projections being removable out of the plane of engagement with the bolt and one of said day-wheel projections being immovable out of said plane.
5. In a time-lock, the combination, substantially as set forth, with clock-driven mechanism and a bolt, of a time-arbor rotated once in forty-eight hours by said time-driven mechanism, a pair of oppositely-disposed projections carried by said time-arbor to lock the bolt twice to each rotation of the time-arbor, and a pair of oppositely-disposed projections carried by said time-arbor to unlock the bolt twice to each rotation of the time-arbor.
6. In a time-lock, the combination, substantially as set forth, with clock-driven mechanism and a bolt, of a time-arbor continuously rotated by said mechanism, a ratchet-wheel *l* carried by said time-arbor, a locking-disk loose on the time-arbor, an unlocking-disk loose on the time-arbor, and pawls *m* upon said disks and engaging said ratchet-wheel, so that the time-arbor drives both disks and either disk may be adjusted upon the time-arbor.
7. In a time-lock, the combination, substantially as set forth, with clock-driven mechanism, a time-arbor continuously rotated thereby and carrying locking and unlocking projections, a bolt, and a spring to throw the bolt to locked position, of a latch arranged to hold the bolt in unlocked position and to be unlatched by said locking projection.
8. In a time-lock, the combination, substantially as set forth, with clock-driven mechanism, a bolt, and a time-arbor driven continuously by said mechanism, of locking and unlocking disks carried by said time-arbor, and separate side spindles geared to said disks to serve in adjusting them on the time-arbor.
9. In a time-lock, the combination, substantially as set forth, with clock-driven mechanism, a bolt, a time-arbor continuously driven by said mechanism, and locking and unlocking disks carried by the time-arbor, of a time-dial carried by the time-arbor, a side dial and pointer geared to the time-arbor and locking-disk, and a second side dial and pointer geared to the time-arbor and unlocking-disk.
